INVENTOR.

RALEIGH H. STALEY.
By Atty. A. Dubois,

UNITED STATES PATENT OFFICE.

RALEIGH H. STALEY, OF SPRINGFIELD, ILLINOIS.

DESIGN FOR A DIE FOR FORMING EDGES OF BRICKS.

SPECIFICATION forming part of Design No. 30,571, dated April 18, 1899.

Application filed March 6, 1899. Serial No. 708,036. Term of patent 14 years.

To all whom it may concern:

Be it known that I, RALEIGH H. STALEY, a citizen of the United States, residing at Springfield, in the county of Sangamon and State of Illinois, have by my own industry, genius, efforts, and expense invented and produced a new, useful, and original shape or configuration of an article of manufacture herein described and known and designated as a Die for Forming the Edges of Bricks, of which the following is a specification, reference being had to the accompanying drawings, forming part hereof, and to the letters of reference marked thereon.

15 My design relates to the art of impressing on a continuous slab or bar of clay emerging in a plastic state from a brick-machine equidistant indentations the length of a brick or the thickness of a brick apart, according as 20 end-cut brick or side-cut brick are being made, said indentations being coincident with the cuts through the slab made by the knife or cut-off wire of the brick-machine and being so formed that when the brick are cut 25 from the slab the side walls of the indentations constitute the rounded edges of the separate bricks.

My said design resides and is embodied in a die for forming the edges of bricks of the 30 form or configuration set forth as a definite article of manufacture.

Referring to the drawings, Figure 1 is a per-

spective view of a die for forming the edges of bricks embodying my design. Fig. 2 is a side elevation of same. Fig. 3 is an end elevation of same, and Fig. 4 is a horizontal section on the line 4 4 of Fig. 2.

For convenience of description I have placed on the drawings letters of reference respectively indicating in the several views like elements of the design.

The main structure or block A is in the form of a parallelepipedon, substantially as shown. One end of the block has convergent concave surfaces a, which unite along the 45 edge a' central to the front end of the block. Extensions A' have outer plane surfaces which are continuations of the corresponding external plane surfaces of the block A. The inner surfaces of the extensions A' are concave and merge into the concave surfaces a, substantially as shown.

That which I have invented and produced and that which I desire to secure by Letters Patent is—

The design for a die for forming the edges of bricks, as herein shown and described.

In witness whereof I have hereunto subscribed my name, at Springfield, Illinois, this 2d day of March, 1899.

RALEIGH H. STALEY.
